UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 20,001, dated July 1, 1890.

Application filed April 15, 1890. Serial No. 348,100. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, and is made somewhat conical, with the smaller end down and the 15 larger end at the top surmounted by a curved plain head B. The body part A is encircled at intervals apart by serpentine bands C, depressed below the surface. The base D is separated from the body part by an annular

band E, and is also provided at the bottom 20 with a second annular band E. This base part D is made round or elliptical, and is shaded on the background and relieved by flower ornamentation G. The body part A is plain, but it may be shaded, if desired. 25

The handle is made of any suitable material.

Having now described my new design, what I claim as new, and desire to secure by Letters Patent, is—

30 The design for cane or umbrella handles, substantially as herein described and shown.

In testimony of which invention I have hereunto set my hand.

HENRY O. SCHMIDT.
